C. F. BERTSCHINGER

TANK SEALING MEANS

Filed Sept. 29, 1926

Fig. 1.

Fig. 2.

INVENTOR
Charles F. Bertschinger
BY
J. H. Shultz
ATTORNEY

UNITED STATES PATENT OFFICE.

CHARLES FREDERICK BERTSCHINGER, OF JAMAICA, NEW YORK, ASSIGNOR OF THREE-FOURTHS TO TIDE WATER OIL COMPANY, OF BAYONNE, NEW JERSEY, A CORPORATION OF NEW JERSEY.

TANK-SEALING MEANS.

Application filed September 29, 1926. Serial No. 138,362.

The invention is an improvement in means for sealing tanks, particularly underground gasoline storage tanks, against fraudulent filling, and for enabling their contents to be 5 gauged, and is more particularly an improvement in the device disclosed in my prior Patent No. 1,604,874, dated October 26, 1926. The object of the present invention is to provide a construction possessing 10 special advantage by reason of its compactness and flatness, adapting it for shallow curb boxes, chambers or recesses at the ground level, and also to provide a construction well adapted for economical manufac- 15 ture, easy to seal, and completely safeguarded against entrance of water into the tank.

In the accompanying drawings forming part hereof:

20 Fig. 1 is an elevation of the upper portion of the pipe which extends upward through the ground from the tank, with the improved construction applied to the upper end of the pipe, the pipe being broken away, most of 25 the length of the measuring rod between its ends being broken away, and a portion of the tank being indicated in section with the lower end of the measuring rod resting on the bottom; and

30 Fig. 2 is a vertical sectional view, showing the rod in elevation.

The pipe 3 rises from an underground tank 2, and may serve for both filling and gauging.

35 A fitting 4 in the nature of a collar having an internal screw thread is screwed onto the upper end of the pipe, and is secured thereto in a permanent or semi-permanent manner, preferably by a pair of set screws 7 connected by a wire and lead seal 8. A removable bushing 10, which is screwed into the fitting, is provided with an aperture 12 which is substantially occupied by a freely 40 raisable gauge rod 6, which extends down through the pipe to the bottom of the tank. The rod has a projecting cross-pin 13 at its lower end, sealed by a seal 14, to prevent the rod from being withdrawn from the opening when the rod is lifted. A similar cross-pin and seal 15, 16 at the upper end of the pipe, together with the provision at the 45 lower end of the rod, insure that the rod can not become separated from the bushing when the bushing is unscrewed from the fitting.

Instead of these particular provisions, the rod might be made with a permanent enlargement or shoulder at one or both ends.

A closure plug 5 prevents entrance of water through the opening 12 and affords access to the upper end of the rod 6, for 50 gauging.

My prior application exhibits similar parts and combinations, but the present construction is decidedly more compact and more desirable by reason of the special features which will be described.

The fitting 4 is made with a laterally projecting flange 25 at its upper end, and this flange is formed with one or more openings 28 designed to have the wire or tape of 70 a seal 20 passed through it. The bushing 10 is a cup-like member, having the aperture 12 in its bottom, and its side wall screw-threaded both outside and inside, the screw plug 5 screwing into the internal thread of 75 this bushing. The top of the bushing has a laterally projecting flange 26 which overlies and cooperates with the flange 25, and is also provided with one or more openings 28, so that the bushing is sealed against unauthorized removal by passing the wire or tape of the seal through the two flanges. The flanges also serve to produce a liquid-tight joint at this point by pressing together 80 against an interposed gasket 27. Another 85 packing 27 is also placed between the flange 26 and a flange 29 of the closure plug.

The bushing 10 and the closure 5 form between them an enlarged chamber 30 for the upper end of the measuring rod with its 90 projection or sealed pin 15, 16.

I claim:

1. Means of the character described comprising a fitting applicable to an entrance of a tank, a removable bushing in said fitting provided with an aperture, a gauge rod occupying said aperture and liftable therethrough but prevented from removal therefrom, means whereby said bushing is sealed against unauthorized removal, and a closure plug which is screwed into said bushing.

2. Means of the character described comprising a fitting applicable to an entrance of a tank, a removable cup-like bushing in said fitting having an aperture in its bottom and an internal screw-thread on its side wall, a gauge rod occupying said aperture

and liftable therethrough but prevented from removal therefrom, means whereby said bushing is sealed against unauthorized removal, and a closure plug which is screwed into the internal thread of said bushing.

3. Means of the character described comprising a fitting applicable to an entrance of a tank, a removable bushing in said fitting provided with an aperture, a gauge rod occupying said aperture and liftable therethrough but prevented from removal therefrom, and flanges on said fitting and bushing providing means for the passage of a sealing element.

10 4. Means of the character described comprising a fitting applicable to an entrance of a tank, a removable bushing in said fitting provided with an aperture, a gauge rod occupying said aperture and liftable therethrough but prevented from removal therefrom, flanges on said fitting and bushing providing means for the passage of a sealing element, and a closure applied to said bushing.

15 5. Means of the character described comprising a fitting applicable to an entrance of a tank, a removable bushing screwed into said fitting and provided with an aperture, a gauge rod occupying said aperture and liftable therethrough but prevented from removal therefrom, and flanges on said fitting and bushing providing means for the passage of a sealing element, said flanges also cooperating in a liquid-tight joint.

20 6. Means of the character described comprising a fitting applicable to an entrance of a tank, a removable bushing screwed into said fitting and provided with an aperture, a gauge rod occupying said aperture and liftable therethrough but prevented from removal therefrom, flanges on said fitting and bushing providing means for the passage of a sealing element, and a closure plug screwed into said bushing and provided with a flange, packing means interposed between the fitting and bushing and another packing means interposed between

the bushing and the flange of the closure plug.

7. Means of the character described comprising a fitting applicable to an entrance of a tank, a removable bushing screwed into said fitting and provided with an aperture, a gauge rod occupying said aperture and liftable therethrough but prevented from removal therefrom, means whereby said bushing is sealed against unauthorized removal, and a closure plug which is screwed into said bushing, said bushing and closure plug forming a chamber between them for the upper end of said rod.

8. Means of the character described comprising a removable fitting secured to the upper end of the pipe of an underground tank, a removable intermediate member applied to said fitting, means enabling said member to be sealed to said fitting against unauthorized removal, said member having an aperture, a gauge rod occupying said aperture and prevented from removal therefrom, and a closure which is applied to said intermediate member.

9. Means of the character described comprising a fitting applicable to the entrance of a tank, a removable bushing in said fitting provided with a gauging aperture, said fitting and bushing having external portions providing means for the passage of a connecting sealing element, and a closure engaged with said bushing.

10. Means of the character described comprising a fitting applicable to the entrance of a tank, a bushing adapted to be screwed into and out of said fitting and provided with a gauging aperture, said fitting and bushing having external portions providing means for the passage of a connecting sealing element, and a closure adapted to be screwed into and out of the bushing, and packing means adapted to be compressed between the fitting and the bushing and between the bushing and the closure.

CHARLES FREDERICK BERTSCHINGER.
